[57] ABSTRACT

The assembly comprises a rotatably mounted capstan member, a pulley member having an annular groove and a line guide means including a gate portion to direct the movement of the line from the capstan member onto the pulley member. The pulley member is mounted to rotate with the capstan member. The line guide means is disposed in fixed relationship with respect to the capstan and pulley members. The assembly of this invention may be used in combination with a power source to form a line pulling device.

ASSEMBLY FOR PULLING A LINE
RELATED APPLICATION

This is a continuation of pending application Ser. No. 105,161 filed Jan. 11, 1971 now abandoned by the same inventor.

BACKGROUND OF THE INVENTION

It is known to use a capstan member around which a line is wrapped and pulled. The line is wound around the rotatably mounted capstan member and is drawn tautly by hand to establish a frictional contact between the line and the capstan member. Where there is a large pulling job necessary, it may take more than one man pulling on the end of the rope in combination with a single capstan to effect the desired results. The size of a pull is thereby limited by the number of men available, the size of the line around which hands may be placed and the size of the capstan member used in combination with the prior art pulling device.

Such a prior art device may be used in a situation where some type of cable is to be pulled through a conduit. In many instances, the cable is plastic coated and will not slide very well through the conduit. Therefore, it is necessary to place some type of lubricant such as grease or soap product on the cable to effect its pulling through a conduit. It is a standard procedure to pull the cable through the conduit by attaching a line such as a braided rope on the end thereof and send this rope through the conduit first. The end of the rope is then wrapped around the capstan member and pulled by hand as the capstan member is rotated under power. Under these prior art circumstances, the lubricant material may get on the lead rope that is being used to pull the cable through the conduit. Obviously there is a tremendous amount of slippage between the rope and the capstan with the friction caused thereby to effect burning of the rope. At the same time, the rope under these circumstances is grinding against itself, causing fraying thereof. Attempts have been made to overcome the problem by pouring some type of abrasive material such as sand on the capstan member while the rope is being manually pulled. However, this procedure has proved to be unacceptable.

Where there is an extremely heavy pull such as would be equivalent to thousands of pounds, the manual pulling of the line would be extremely difficult. There is obviously the necessity for the stopping and restarting of the pulling of the line as the men handling the end of the rope must rest between pulls. This procedure is necessary even though the rotation of the capstan member helps to effect the pull once the line is frictionally engaged therewith.

PURPOSE OF THE INVENTION

The primary object of this invention is to provide an assembly which will facilitate the handling of a line that is being pulled in many different situations.

Another object of this invention is to provide an assembly which has a potential unlimited capacity to pull a line.

Another object is to provide an assembly which will effect a continuous pulling of the line without intermittent starting and stopping thereof.

It is a further object of this invention to provide an assembly for pulling a line such as a wire or cable through the use of a mechanical combination only.

5 A further object is to provide an assembly used in combination with a pulling device which reduces manpower, overcomes line wear and reduces safety hazards on vertical lifts.

SUMMARY OF THE INVENTION

These objects and other advantages are accomplished through the use of an assembly comprising a rotatably mounted capstan member, and a pulley mechanism having an annular groove. The pulley mechanism is mounted to rotate with the capstan member. A line guide means is disposed in fixed relationship with respect to the capstan and pulley members to effect various types of functions. The line guide means includes a gate portion to direct the movement 10 of the line from the capstan member onto the pulley mechanism.

In one specific embodiment, a jib sheet winch is used on sailboats for pulling the line taut through the use of a 15 crank mechanism. Such a winch has proven to effect a fast and safe pulling of the jib sheet sail line. Tailing can be accomplished very easily and the winch can be 20 operated by one person even under the toughest conditions.

In another specific embodiment, the mechanical 25 combination as set forth hereinabove is operatively connected to a power source for effecting heavy pulls such as the pulling of wire or cable through conduits. The basic assembly of this invention may be used on any prior art device in place of the standard capstan element presently used thereon. In addition, any 30 completely new pulling device may incorporate the assembly or mechanical combination as disclosed herein.

In a further specific embodiment of this invention, my patented pulley as disclosed in U.S. Pat. No. 3,343,809 is used as the pulley member to effect a positive, non-slip mechanism for pulling a rope having a substantial resistance or load. This specific embodiment is particularly useful with braided ropes that will mesh with the ribs and troughs that are disposed transversally to the circumference of the annular groove in the pulley member. The meshing arrangement is designed to enhance the gripping action on the rope placed in the annular groove. The particular design of the specific embodiment as disclosed herein eliminates the frictional pull on such a braided rope and establishes a positive non-friction engagement between the pulley member and the braided rope.

BRIEF DESCRIPTION OF DRAWINGS

Other objects of this invention will appear in the following description and appended claims, reference being made to the accompanying drawings forming a part of the specification wherein like reference characters designate corresponding parts in the several views.

FIG. 1 is a side elevational view of an assembly made in accordance with this invention,

FIG. 2 is an end view of the device as shown in FIG. 1 and

60 FIG. 3 is a perspective view of a specific embodiment of a line pulling device made in accordance with this invention.

DESCRIPTION OF SPECIFIC EMBODIMENTS

More specifically, a capstan member 4 is rotatably mounted on the central standard or centerpost 24. The centerpost 24 acts as a base portion for other rotating and stationary parts. A pulley member 18 is secured to the capstan member 4 and rotates therewith around the centerpost 34. The centerpost 24 is a fixed, cylindrical shaft or column about which the capstan member 4 and pulley member 18 freely rotate. In this specific embodiment, the pulley member 18 has a V-shaped annular groove (not numbered). A plurality of ribs and troughs is disposed transversally to the circumference of the annular groove and at regular intervals along the surface thereof in accordance with the disclosure of my U.S. Pat. No. 3,343,809 issued Sept. 26, 1967. While all types of pulleys may be used as the pulley member 18 in my invention, it has been found that the specific use of the pulley member as shown in FIG. 1 in combination with the capstan member with which it rotates in unison around the shaft 24 will effect pulling results heretofore unobtainable in prior art devices.

A particular feature of this invention is that the pulley member 18 must rotate in unison with the capstan member 4. In the specific embodiment as shown in FIG. 1, if the pulley member 18 were freely rotatable, the assembly as shown would be inoperative. It is contemplated, however, that various types of drive mechanisms may be used to rotate the capstan member 4 and the pulley member 18 to effect the desired results. As seen in the drawings, any desired mechanism may be used to provide the rotatable mounting of the capstan member 4 and the pulley member 18.

As seen in the drawings, the relative diameter of the capstan member 4 is slightly larger than the effective diameter of the operating pulley with the line 6 disposed therein. This type of relationship is established so that the appropriate type of pull will be made on the line 6 which is wrapped around the capstan member 4. There must be an additional friction established between the line 6 and the capstan member 4. The relative diameters are established so that the line 6 is not pushed out of engagement with the pulley member 18 during the rotation thereof around the centerpost 24. The effective diameter of the operating pulley member 4 with the line 6 placed therein is smaller than the diameter of the capstan member 4 by an amount sufficient to distribute the load on the capstan member 4 and pulley member 18. It is important to establish a frictional contact between the capstan member 4 and the line 6 so that the capstan member 4 will effectuate a substantial portion of the load being pulled.

Another feature of this invention is directed to the line guide means which comprises a stationary entry guide means or gate portion 10, bracket portion 16 and disengagement means 12. As is evident in the drawings, the gate portion 10 extends in a direction transverse to the periphery of the capstan member 4 and pulley member 18. In this specific embodiment, a disk or ring configuration 10 is disposed between the capstan member 4 and the pulley member 18. At least a section of the disk or ring member 10 extends outwardly beyond the peripheries of the capstan member 4 and the pulley member 18. A gate portion is formed between the guiding surfaces or edges 20 and 22 to

direct the movement of the line 6 from the capstan member 4 onto the pulley member 18 when the assembly is in operation.

The gate portion is formed as an opening in the peripheral section of the disk or ring member 10. The disk member 10 is stationary with respect to the rotatable capstan member 4 and pulley member 18. The disk member 10 is held in position by the bracket 16 in this specific embodiment. Various types of structures may be used to establish the gate portion so long as it accomplishes the desired results of directing the movement of the line 6 onto the pulley member 18 after it leaves the capstan member 4. The structural configuration of the disk or ring member 10 is effective to allow the capstan member 4 and pulley member 18 to revolve without the ring member 10 itself turning.

A further feature of an assembly made in accordance with this invention is directed to the bracket portion 16 which fixes the position of the disk member 10 through its attachment to the centerpost 24. The position of the guiding edges 20 and 22 remains fixed because the one end of the support bracket 16 is joined to the centerpost or shaft 24 by the fasteners 26. In this specific embodiment, the bracket or support member 16 may be a steel bracket disposed adjacent to the exposed lateral surface of the pulley member 18. The bracket 16 has a right angle bend in its body so that a portion extends over the annular groove of the pulley member 18. The distal end of the support or bracket 16 fits into a recess 8 located in the peripheral portion of the disk or ring member 10 to hold it in place.

A further feature of this invention is the use of a line disengagement means 12 which is mounted within the annular groove of the pulley member 18. The line departure guide or disengagement means 12 has an opening 14 through which the bracket or support 16 passes to hold the disengagement means 12 in place. A finger portion 12a extends downwardly in this specific embodiment to engage the line 6 along the releasing surface 32. It has been found that the finger portion 12a should be located at least 180° away from the guiding edge 22. The line guide means of this assembly includes the gate portion, bracket portion and disengagement means.

While the embodiment as shown in FIGS. 1 and 2 may be driven by a motor power source 2, the embodiment incorporating the assembly of this invention is shown in a jib winch structure 34. The capstan and pulley members 4 and 18, respectively, are rotated by the manual crank 36. In operation, a braided rope 6 constituting a line is first wound around the capstan member 4 one or more times. The greater the load being pulled, the more times the line 6 should be wound around the capstan member 4. The line 6 is then guided through the gate portion between the guiding edges 20 and 22 into the annular groove of the pulley member 18. The line 6 is placed in the assembly in the direction illustrated by the arrows. Upon turning the crank and handle mechanism 36, the line 6 meshes with the rib and trough structure of the pulley member 18 and a load is placed on the line to effect a frictional contact between the line 6 and the rotatable capstan member 4. This action enables a portion of the load to bear upon the capstan member 4 and another portion to bear upon the pulley member 18.

In this specific embodiment, the ribs and troughs of the pulley member 18 mesh with the braided rope to enable the pulling of extremely large loads. Heavy loads force the rope 6 in the direction of the apex 28 of the V-shaped annular groove. The space 30 between the apex 28 and the line 6 tends to be reduced in direct ratio to the size of the load. Upon continued rotation, the finger 12a of the disengagement means 12 automatically disengages the line 6 from the pulley member 18. The finger member 12a is positioned in the space 30 so that the rope 6 must bear on its releasing surface 32.

While the assembly for pulling a line has been shown and described in detail, it is obvious that this invention is not to be considered as being limited to the exact form disclosed, and that changes in detail and construction may be made therein within the scope of the invention, without departing from the spirit thereof.

Having thus set forth and disclosed the nature of this invention, what is claimed is:

1. An assembly for pulling a line comprising:
  - a. a capstan member and a pulley member rotatably mounted around a stationary center post,
  - b. said pulley member having an annular groove and mounted to rotate with said capstan member, and
  - c. line guide means including a gate portion to direct the movement of the line from the capstan member onto said pulley member,
  - d. said line guide means being disposed in fixed relationship with respect to the capstan and pulley members,
  - e. the gate portion includes a disk member disposed between the rotatably mounted capstan member and a pulley member, and
  - f. the line guide means includes a bracket portion extending from the disk member to the center post to fix the position of the disk member with respect to the rotatable capstan and pulley members.
2. In a device wherein a power source is operatively connected to a mechanical combination for pulling a line, said mechanical combination comprising:
  - a. a capstan member and a pulley member rotatably mounted around a stationary center post,
  - b. said pulley member having an annular groove and mounted to rotate with said capstan member, and
  - c. line guide means including a gate portion to cause the line to move from the capstan onto said pulley member,
  - d. said line guide means being disposed in fixed relationship with respect to the capstan and pulley members,
  - e. said pulley member including a plurality of ribs and troughs disposed transversely to the circumference of the annular groove and at regular intervals along the surface thereof,
  - f. said gate portion includes a disk member disposed between the rotatably mounted capstan member and pulley member,
  - g. at least a section of the disk member extends outwardly from the periphery of the capstan and pul-

55

60

ley members and has an opening therein located to direct movement of the line from the capstan member to the pulley member,

- h. said line guide means includes a bracket portion extending from the disk member to the stationary center post to fix the position of the disk member with respect to the rotatable capstan and pulley members.
3. A pulley assembly for pulling a line comprising;
  - a. a rotatably mounted capstan member,
  - b. a pulley member having an annular groove and mounted to rotate with said capstan member, and
  - c. line guide means including a disk member fixedly disposed between the rotatably mounted capstan member and pulley member,
  - d. at least a section of said disk member extending outwardly beyond the peripheries of the capstan and pulley members and having an opening through which the line moves onto the pulley member after it leaves the capstan member.
4. An assembly for pulling a line comprising;
  - a. a capstan member and a pulley member which are mounted to rotate about a common axis of rotation,
  - b. the pulley member having an annular groove and being adapted to rotate in unison with said capstan member, and
  - c. line guide means disposed in fixed relationship with respect to the capstan member and the pulley member,
  - d. said line guide means including a gate portion to direct the movement of the line from the capstan member onto said pulley member,
  - e. said gate portion extending in a direction transverse to the periphery of the capstan member and the pulley member and along which gate portion the line moves as it winds directly onto the pulley member after it leaves the capstan member.
5. An assembly as defined in claim 4 wherein said gate portion includes an opening through which the line moves as it winds onto the pulley member after it leaves the capstan member.
6. An assembly as defined in claim 4 wherein said gate portion includes two guiding surfaces between which the line moves as it winds onto the pulley member after it leaves the capstan member.
7. An assembly as defined in claim 4 wherein the line guide means includes a means to disengage the line from the annular groove of the pulley member after the line has moved from the capstan member to the pulley member.
8. An assembly as defined in claim 4 wherein the pulley member includes means disposed within the annular groove to enhance the gripping action on the line.
9. An assembly as defined in claim 4 wherein a plurality of ribs and troughs is disposed transversally to the circumference of the annular groove and at regular intervals along the surface thereof.

[57] **ABSTRACT**

The assembly comprises a rotatably mounted capstan member, a pulley member having an annular groove and a line guide means including a gate portion to direct the movement of the line from the capstan member onto the pulley member. The pulley member is mounted to rotate with the capstan member. The line guide means is disposed in fixed relationship with respect to the capstan and pulley members. The assembly of this invention may be used in combination with a power source to form a line pulling device.
